BOTTLE CARRYING CASE

James M. Andrews, Robinson Township, Allegheny County, Pa., assignor to Sinclair-Koppers Company, a uniform partnership of Delaware

Filed Dec. 5, 1966, Ser. No. 4,918

Term of patent 14 years

(Cl. D58—26)

The figure is a perspective view of a bottle carrying case showing my new design as seen from the front and side. The rear of the article is identical in appearance to the front, and the side away from the side shown in the drawing is identical in appearance to the side shown in the drawing.

The bottom of the bottle carrying case is substantially plain and unornamented.

I claim:

The ornamental design for a bottle carrying case, as shown and described.
